(57) **CLAIM**

The ornamental design for a mobile phone, as shown and described.

DESCRIPTION

FIG. 1 is a perspective view of a mobile phone illustrating our new design;

FIG. 2 is a front elevation view thereof;

FIG. 3 is bottom plan view thereof;

FIG. 4 is a rear elevation view thereof;

FIG. 5 is a top plan view thereof; and,

FIG. 6 is a side elevation view thereof.

In the drawing, the broken lines immediately adjacent the shaded surfaces represent boundaries of the claimed design. All other broken lines depict unclaimed environment. The broken lines and unshaded regions that are bounded by broken lines form no part of the claimed design.

1 Claim, 3 Drawing Sheets
